FISHING POLE HOLDER

Gerald J. Curtis, 8806 Glen Loch,
Houston, Tex. 77017

Filed Nov. 2, 1972, Ser. No. 303,268

Term of patent 14 years

Int. Cl. D22—05

U.S. Cl. D22—14

FIG. 1

FIG. 2

FIG. 3

FIG. 1 is a perspective view of a fishing pole holder, the opposite side being the same except for the absence of the strap holders;

FIG. 2 is a front perspective view showing a modified form of the design wherein a loop is provided for a fish stringer holder;

FIG. 3 is a bottom view of FIG. 1.

The straps have been shown broken away for convenience of illustration.

I claim:

The ornamental design for a fishing pole holder, as shown and described.
